RADIO COMMUNICATION SYSTEM

Earl L. Koch, Chicago, Ill., assignor, by mesne assignments, to Earl L. Koch Holding Corporation, New York, N. Y., a corporation of New York

Application December 31, 1929, Serial No. 417,684

6 Claims. (Cl. 250—17)

This invention relates to high frequency radio communication systems, and it has among its objects the provision of improved radio transmitting and radio receiving systems capable of operating 5 on much narrower frequency bands than those used heretofore, and thereby enabling the establishment of a much larger number of practically useful communication channels within the available radio spectrum.

10 The novel features and principles of the invention will best be understood from the following description of a radio communication system exemplifying the invention, reference being had to the accompanying drawings wherein

15 Figs. 1 and 2, when placed end to end, with Fig. 1 to the left, illustrate diagrammatically a five channel radio transmitting system embodying the invention; and

20 Figs. 3 and 4, when placed end to end, with Fig. 3 to the left, illustrate a five channel radio receiving system embodying the invention.

25 In point to point radio telegraph communication systems, messages are transmitted over definitely assigned frequency channels which are allocated to the stations of the systems. Each channel is of a definite mean frequency and the stations operating within the channel are not permitted to deviate from this mean frequency beyond a predetermined degree.

30 At the present time, there is available for point to point communication systems in the high frequency range the frequency band extending from 1500 kilocycles to 23,000 kilocycles. Of this frequency range, the band extending from 1500 35 kilocycles to 6000 kilocycles is known as the continental high frequency band and has been assigned for use in point to point communication over the continent.

40 In the present state of the art, it is generally considered that the separation between the mean frequencies of the individual communication channels in these bands must be 0.2% of the frequency assigned to a particular channel. Thus, a channel having an assigned frequency of 6,000 45 kilocycles must include a frequency band of 12 kilocycles. The communication system of the present invention has been developed for use in communication over channels in the continental high frequency band and has proven to be capable of practically operating with a channel 50 separation which is only one-fifth of the channel separations heretofore deemed practicable. However, the invention is not limited to this specific increase of the channel number practicable within 55 the range of frequencies available for com-

mercial use, nor to the particular frequency band, but its features are applicable and useful to improve radio communication systems, to decrease the channel separation necessary for efficient operation of such systems, and to generally provide more efficient, simple and reliable radio communication between widely spaced points. Through the use of the invention, it is possible to provide many more communication channels within the available radio spectrum than with 10 the systems known heretofore, each channel being capable of operating without interfering with the adjacent channels and without being disturbed by signals transmitted in these channels.

15 For purposes of illustration, it is assumed that there was made available for communication purposes one of the official short wave channels, say a channel having a frequency of 5,875 kilocycles. On the basis of the permissible deviation of 2% of the assigned frequency, this channel 20 will have assigned for its use a frequency band extending from 5,869.125 kilocycles to 5,880.875 kilocycles. By utilizing the apparatus and arrangements of the invention, I have obtained practical point to point commercial telegraphic 25 communication within the band of frequencies assigned to such channel through five distinct communication subchannels, each subchannel operating in the same way as a normally assigned channel 30 is intended to operate. In practice, it has been found convenient to have these subchannels separated by a frequency band of 750 cycles, although a larger number of subchannels may be provided within the assigned frequency band by following 35 the principles of the invention.

40 In the drawings, there is illustrated such five subchannel communication systems intended to operate with a frequency separation of 750 cycles between the individual subchannels. Assuming, for the purpose of illustration, an assigned frequency of 5,875 kilocycles, the individual subchannels are arranged to operate so that the first subchannel operates with a frequency of 5,873.50 kilocycles, the second subchannel with a frequency of 5,874.25 kilocycles, the third subchannel with a frequency of 5,875.00 kilocycles (this being the assigned channel frequency), the fourth subchannel with a frequency of 5,875.75 kilocycles, and the fifth subchannel with a frequency of 5,876.50 kilocycles.

45 In the drawings, the five subchannels of the transmitting system shown in Figs. 1 and 2 and the five subchannels of the receiving system shown in Figs. 3 and 4 are identified by numerals C1 to C5.

The individual subchannels are, in general, provided with the same kind of apparatus, and they are arranged in the same way, so that it will only be necessary to describe in detail the 5 apparatus and arrangement of a single subchannel and point out only its relationship to the apparatus and the arrangements of the other subchannels in order to fully understand the invention.

10 The transmitting system comprises the transmitting apparatus which is shown in Fig. 2 and the monitoring apparatus which is shown in Fig. 1. The transmitter apparatus comprises a transmitting oscillator TO in which is maintained a 15 continuous high frequency oscillation of the frequency on which the particular subchannel C1 is to operate, a transmitter amplifier TA in which the high frequency oscillations maintained in the transmitting oscillator are amplified and subjected to control action, such as keying, for transmission of signals; and a transmitter power amplifier TPA in which the oscillatory output of the transmitter amplifier TA is further amplified to a value sufficient to secure radiation that would 20 reach the point with which the particular channel is to maintain communication. The power amplifier is associated with suitable radiating apparatus, such as an antenna RA.

The transmitting oscillator TO comprises a 30 pair of audion tubes V1, V2 of the four-element or screen-grid type including, respectively, filamentary cathodes 2, 3, control grids 4 and 5, anodes or plates 6 and 7, and screen grids 8 and 9. The cathodes 2 and 3 are supplied with heating 35 current from a suitable source, such as a cathode heating battery 10, one leg of the cathode filaments being connected to a grounded bus bar which is indicated on the drawings by the letter G. In the output circuits of the two tubes V1, 40 V2 are connected resonant tank circuits LC1, LC2 formed of inductances 11 and condensers 12. Plate current is supplied to the output circuits of the two tubes V1, V2 from a suitable source of uni-directional current such as a battery 14 which 45 is connected to the two plate circuits through high frequency chokes 15, 16. A bridging condenser 18 and 19, respectively, between each tank circuit and cathode provides a by-pass for the high frequency currents and completes the output 50 circuit of each tube.

The input circuits of the two tubes V1 and V2 comprises impedances 20, 21, respectively, and by-pass condensers 22, 23. Biasing means such as batteries 24 serve to maintain the grids of the 55 tubes at a suitable operating potential with respect to the cathodes. The screen grids 8 and 9 of the two tubes V1, V2 are connected to the cathodes through by-pass condensers 26 and are maintained at a positive potential against the 60 cathodes through a connection to a suitable tap 28 on the plate battery 14 to prevent feed-back from the output circuit to the input circuit of each tube through the inter-electrode capacity.

The two tubes V1, V2 with their associated 65 circuits are coupled into a ring circuit by means of coupling condensers 29, 29¹ connected between the control grid of the one tube and output circuit of the other tube, respectively.

The two tank circuits LC1 and LC2 are tuned 70 to the frequency of the oscillation that is to be used in the particular subchannel. Each tank circuit will accordingly form a filter unit or section which will maintain and build up oscillations of the frequency to which it is tuned but will suppress and absorb other frequencies. The cou-

pling between the input circuit of each tube and the output circuit of the preceding tube in the ring circuit may be made through the medium of adjustable taps 30, 31 on the inductances 11 of the tank circuits LC1, LC2. This coupling is made weak so that only a small amount of the energy of the output circuit of one tube is impressed upon the input circuit of the next successive tube of the ring circuit.

A circuit arrangement as described above when 10 used in the way herein described acts as a very exact stabilizer of high frequency current oscillations. This action results from the fact that the oscillatory currents are continuously recirculated through filter circuits which are resonant 15 to the desired frequency but absorb or are opaque to all other frequencies. There is thus formed, in effect, a filter with an infinite number of filter sections. The electron tubes serve to secure one-way circulation of the current through the filter 20 sections so as to compel the currents to pass over again and again through the filter sections where the currents of the frequency to which the circuit is tuned is built up and all other currents are suppressed. For the effectiveness of this arrangement it is important that the electron tubes which 25 are used as coupling means shall not feed back energy directly from the output electrodes into the input electrodes without passing it first through the filter circuits.

This stabilizing high frequency oscillator thus forms a reentrant ring oscillator having filter elements and amplifier tubes interconnected in a ring circuit to continuously re-feed the current only in one direction, the individual amplifier 30 tubes being connected to derive only a small amount of energy from the preceding filter section and to supply it in amplified form to the next filter section, under substantial elimination of 35 direct feed back between the output and input electrodes of the individual tubes.

In accordance with my invention I employ such 40 reentrant ring oscillator as a primary oscillator for each communication subchannel to stabilize the oscillations within the subchannel. I have 45 found that such reentrant ring oscillator retains a particularly high degree of stability if used with low energies and when so used it will maintain the frequency of the oscillations for which the filter circuits are designed with an extremely high 50 degree of accuracy. According to the invention 55 such reentrant ring oscillator operating with low energy is utilized to obtain high power oscillations suitable for radio transmissions in signalling systems by applying oscillatory energy from such ring oscillator to the input electrodes of a power amplifier the output of which is to be used for radiation. In the preferred arrangement, the oscillatory energy derived from the stabilized ring oscillator is first impressed upon an intermediate 60 amplifier arranged to permit signalling by keying or modulating of the high frequency oscillations passing through the amplifier. The modulated output of this intermediate amplifier is then impressed upon a power amplifier which delivers 65 its oscillatory energy to the antenna. By such arrangement disturbing reactions resulting from the modulations of the power delivered to the high frequency radiator are prevented from influencing the operation of the ring circuit oscillator while the ring circuit, on the other hand, retains full stabilizing control of the oscillations. Furthermore, disturbance of the ring oscillator and its stability, due to keying or modulation of the output of the intermediate amplifier is pre-

vented by arranging the keying or modulating means so as to prevent feed-back or reaction on the ring oscillator.

In the embodiment of the invention shown in the drawings the intermediate amplifier TA consists of three impedance-coupled amplifier stages including three audion tubes V3, V4 and V5. These audion tubes are of the screen grid type and comprise, respectively, filamentary cathodes 36, 37, 38, control grids 39, 40, 41, anodes or plates 42, 43, 44 and screen grids 45, 46, 47 with associated elements including cathode-heating source 48, plate current source 49, grid-biasing source 50, high frequency choke coils 51, 52, 53, and by-pass condensers 54, 55, 56. Input impedances in the form of inductances 57, 58, 59 are connected, respectively, in the input circuits of the three tubes V3, V4, V5, and in the output circuits are connected tank circuits LC3, LC4, LC5, composed of inductances 60 and 61. The control grid 39 of the first tube of the intermediate amplifier stage is connected to a tap on the inductance 11 of the tank circuit LC2 of the ring oscillator TO, and the input electrodes of the further amplifier tubes V4, V5 are similarly connected to the inductances 60 in the tank circuits of the preceding amplifier tubes, blocking condensers 62, 63, 64 being provided in the several connections, respectively.

In the output circuit of amplifier tube V5 of the last stage of the intermediate amplifier TA there is provided a transmitter key TK by means of which the uni-directional current supply source 49 may be cut off from the plate circuit of the last tube. In this way the oscillation in the last stage of the intermediate amplifier may at any time be cut off or established by opening or closing the key TK.

The so modulated output from the intermediate amplifier TA is impressed upon a final power amplifier stage TPA comprising a screen grid amplifier tube V6, having a cathode 70, a control grid 71, anode 72 and screen grid 73 with the associated cathode-heating source 74, a plate current source 76, high frequency choke coil 77 and by-pass condensers 78, 79, 80. A tank circuit LC6 comprising an inductance 81 and a condenser 82 is connected in the input circuit of the tube, and a tank circuit LC7 comprising an inductance 83 and a condenser 84 is connected in the output of the tube. The output of the last tube V3 of the intermediate amplifier is impressed upon the input circuit of the power amplifier TPA through a coupling connection 85 including a blocking condenser 86. The output circuit of the power amplifier tube V6 is connected with the radiating antenna RA by means of a coupling transformer 87, which is preferably connected to the midpoint of the antenna through condensers 88 and is arranged to permit balancing of the currents in the two antenna halves and to adjust the degree of coupling with the output circuit of the amplifier tube.

The several amplifier stages TA and TPA are so arranged that they shall not by themselves come into an oscillatory state, and with this in view the several screen grid electrodes are connected and adjusted to prevent feed-back from the output circuits to the input circuits. The tank circuits LC3 to LC7 are preferably resonant to the frequency of the particular subchannel so as to exercise a further discriminating effect, although there may be used untuned or aperiodic circuits that merely cooperate to amplify the oscillatory input received from the reentrant ring oscillator.

In operating a transmitter of the type described above the reentrant ring oscillator TO is caused to oscillate with low energy, the tank circuits LC1 and LC2 being tuned to the frequency on which the subchannel is to operate. Energy from this stabilized ring oscillator is impressed upon the intermediate amplifier TA with its stages V3, V4, V5 where the weak energy received is amplified to a substantial value and is keyed so as to produce the desired signals. The point where the keying is effected is so chosen as to prevent disturbing reactions that might be caused by the keying from affecting the operation of the ring oscillator TO, and it is for this reason that one or more amplifier tubes V3, V4 are connected between the stage where the keying is done and the ring circuit. The keyed high frequency oscillations from the last stage of the intermediate amplifier are then conveyed to the power amplifier TPA where the oscillatory energy is further amplified to a value at which the desired radiation will be produced.

As indicated in the drawing the subchannels C2, C3, C4, C5 have transmitting oscillators TO and intermediate transmitting amplifiers TA which are duplicates of the apparatus used in the subchannel C1. One power amplifier TPA may be used for several subchannels, and in the drawings the outputs of the intermediate amplifiers TA of all the five subchannels are shown connected to the common coupling conductor of the power amplifier TPA so as to impress the output of all the five subchannels on the same power amplifier. Where the input or output circuits of the power amplifier TPA are tuned, the tuning is made sufficiently broad to prevent discriminatory action against the high frequency currents received from the several subchannels operating on the same power amplifier. The individual high frequency channels are keyed separately and their combined input is impressed upon the amplifier. As a result the output of the power amplifier that is impressed upon the radiating antenna will represent a resultant of the oscillations impressed by the individual subchannels which operate on it.

Although in certain applications it may be desirable to operate a plurality of intermediate amplifiers of different subchannels with a single power amplifier of broad tuning to cover the range of the several subchannels operating on it, I prefer in ordinary point to point transmission, to use a separate power amplifier for each of the subchannels. With such arrangement each subchannel has its own transmitting oscillator TO, its own intermediate amplifier TA with keying arrangement, and its own transmitting power amplifier TPA. The radiating antenna may be used in common for all the subchannels, or a separate radiating antenna may be used for each subchannel. Where the radiating antenna is used in common, it is made so as to avoid any discriminatory effect on the individual frequencies that are to be radiated by it.

In order to supervise the operation of the transmitting apparatus, it has associated therewith the monitoring system shown in Fig. 1 of the drawings. The monitoring system of the subchannel C1 is shown in detail, and comprises a monitor beat oscillator MBO, a monitor beat receiver MBR, a monitor beat selector MBS, a standard monitor oscillator SMO and a monitoring stage MU.

The monitor beat oscillator MBO comprises an audion tube V7 having a cathode 90, a control

grid 91, and an anode 92 with the associated cathode heating source 93, plate source 94 and by-pass condenser 95. A tuned tank circuit LC8 comprising an inductance 96 and a condenser 97 is connected in the output circuit of the audion tube V7 and a piezo-electric crystal oscillator 98 is connected in the input circuit of the audion tube in such manner as to produce in the tank circuit LC8 a continuous oscillation at the frequency of the crystal oscillator 98. This monitor beat oscillator is so arranged and adjusted that the frequency of its oscillations differs slightly from the frequency of the oscillations produced by the transmitter apparatus so that when the frequency of the monitor beat oscillator is combined with the frequency of the transmitter oscillator a beat frequency will result which is preferably within the audible range. For instance, assuming that the frequency of the transmitting subchannel C1 is 5,875.00 kilocycles, the beat oscillator MBO is adjusted to oscillate at a frequency of 5,872.375 kilocycles, giving a beat frequency of 2625 cycles.

This beat frequency is produced in the monitor beat receiver MBR which comprises an audion tube V8 having a filamentary cathode 100, a control grid 101, an anode 102 with the associated cathode-heating source 103, plate supply source 104 and by-pass condensers 105, 106. Oscillations from the reentrant ring oscillator TO of the transmitter are impressed upon the input electrodes of the monitor beat receiver MBR by means of the coupling coil 107 arranged to be variably coupled to the coil 20 in the input circuit 35 of the tube V1 of the ring oscillator. Oscillations from the monitor beat oscillator are simultaneously impressed upon the monitor beat receiver MBR by means of a coupling circuit 108 including a coil 109 coupled to the inductance 96 40 in the tank circuit LC8 of the monitor beat oscillator MBO and a coil 110 coupled to a coil 111 that is connected in the input circuit of the monitor beat receiver, being arranged in series with the coupling coil 107 of the ring oscillator TO. 45 A condenser 112 connected in shunt to the circuit including the coupling coils 107 and 111 serves to adjust the input circuit to secure optimum operation conditions. The circuits of tube V8 are adjusted, as by suitable bias on grid 101, 50 to deliver rectified beat oscillations on the output side to an audio frequency transformer 113 through which the oscillations are impressed on the monitor beat selector MBS.

The monitor beat selector MBS comprises two 55 cascade coupled screen-grid audion amplifiers V9 and V10 having cathodes 115, control grids 116, anodes 117 and screen grids 118, with the associated cathode heating source 119, plate current source 120, choke coils 121 and by-pass condensers 122, 123. In the plate circuits of the two tubes are connected tank circuits LC9 and LC10 formed of inductance coils 125 and condensers 126, the tank circuits LC9 and LC10 being tuned to resonance with the beat frequency of the particular channel. The input electrodes of audion tube V9 are coupled to the output circuit of the monitor beat receiver by a variable tap connection 127 on a coupling resistor 128 connected to the output transformer 113. The input electrodes of the audion tube V10 are similarly connected through a variable tap resistor 129 to the output circuit of the audion tube V9, a blocking condenser 130 being interposed in the connection. 70

A standard monitor oscillator SMO associated 75 with the subchannel is arranged to produce an

oscillation of the same frequency as the beat note derived from the monitor beat selector MBS in this particular instance, an oscillation of 2625 cycles. The standard monitor oscillator comprises two tubes V12, V13, having cathodes 140, anodes 142, control grids 143 with associated cathode heating source 145 and plate current source 146. In the input circuits of the two tubes V12, V13 are connected tank circuits LC12, LC13 composed of inductances 147 and condensers 148 10 tuned to the frequency of the oscillation, in the present instance, to frequency of 2625 cycles. The two audion tubes V12, V13 are coupled in a ring circuit in a way similar to the transmitter oscillator TO, the plate 142 of one audion tube being connected to the grid 143 of the other audion tube through connectors including current limiting resistors 151 and blocking condensers 152. Audio frequency choke coils 153 and bypass condensers 154 complete the circuits. 15

This arrangement of the two valves V12, V13 in a ring circuit will result in generation of oscillations of a frequency of the tank circuits LC12, LC13 in a manner similar to the operation of the transmitter oscillator TO, the oscillations 25 being very stable at the particular frequency of the tank circuits and being practically unaffected by disturbances that tend to vary or shift the frequency of the oscillations.

The outputs of the monitor beat selector MBS 30 and the standard monitor oscillator SMO are impressed on two tubes V11, V14 of the monitoring unit MU in such manner as to permit comparing of the frequencies of these two outputs and ascertain as to whether the beat oscillation differs from 35 the standard monitor oscillation or not. Audion tubes V11 and V14 each comprise a cathode 161, an anode 162, control grid 164 with associated cathode-heating source 165 and plate current source 166. The input electrodes of tube V11 are 40 coupled to the output circuit of the monitor beat selector by a connection including a variable tap impedance 167 and blocking condenser 168. The input electrodes of the audion tube V14 are similarly connected to the output circuit of the tube 45 V13 of the standard monitor oscillator SMO by a variable tap resistor 169. The output circuits of the two tubes V11 and V14 are impressed through coupling transformers 171 and 172 on a monitoring device 173 which is arranged to be actuated 50 by the two frequencies received from monitor beat selector MBS and standard monitor oscillator SMO, respectively, to indicate any departure from the standard. As shown in the drawings, provision may also be made for connecting additional auxiliary apparatus such as head telephone sets to the output circuits of the two audion tubes V11 and V14, as by means of telephone jacks 174 and 175, permitting direct comparison of the 55 two audio frequencies by telephone.

In the foregoing arrangement, the monitoring system maintains a continuous supervision of the operation of the transmitting apparatus of each subchannel. Simultaneously with the generation of high frequency oscillations in the transmitter oscillator TO a part of its output is impressed upon the monitor beat receiver MBR where this output is combined with the output of the monitor beat oscillator MBO. The resulting beat note is then picked out by the monitor beat selector MBS and delivered in amplified form to the monitoring unit MU that independently receives oscillations from a standard oscillator SMO which is so set that by comparison of its frequency with that of the beat note in the monitoring unit MU, it is immediately 60 65 70 75 80 85 90 95 100 105 110 115 120 125 130 135 140 145 150 155 160 165 170 175 180 185 190 195 200

possible to determine whether the transmitter oscillator TO is in time and operates within its assigned frequency band or has deviated therefrom, necessitating corrective adjustments.

5 In the drawings I have shown the monitor beat oscillator MBO in the form of a piezo crystal oscillator and the standard monitor oscillator SMO in the form of a special reentrant ring oscillator. For the satisfactory operation of the monitoring 10 system both the monitoring beat oscillator and the standard monitor oscillator must maintain their frequency very closely and operate stably without deviations from their predetermined frequencies. Instead of a piezo electric oscillator, 15 a reentrant ring oscillator may be used as a monitoring beat oscillator; and conversely, a piezo electric oscillator may be employed as a standard monitoring oscillator SMO.

Where the apparatus for each subchannel is 20 made complete in itself, each subchannel will have its own monitoring beat oscillator MBO, monitor beat receiver MBR, monitor beat selector MBS, standard monitoring oscillator SMO and monitoring unit MU. However, where several 25 subchannels are combined as in the arrangement illustrated in the drawings, a single monitor beat oscillator may be used for several subchannels. Assuming the instance referred to above, where the five subchannels are arranged for operation 30 at 5,872.50 kilocycles, 5,874.25 kilocycles, 5,875.00 kilocycles, 5,875.75 kilocycles and 5,876.50 kilocycles, the monitor beat oscillator is arranged so as to oscillate at a frequency which will permit combination of its oscillations with the frequencies of the several subchannels so that for 35 each subchannel there is produced a monitoring beat oscillation of an audible frequency. Thus in the specific case mentioned, the monitoring beat oscillator may be set for operation at a frequency of 5,872.375 cycles, giving for the five 40 subchannels beat oscillations of 1125 cycles, 1875 cycles, 2625 cycles, 3375 cycles and 4125 cycles. In order to secure satisfactory operation and permit a proper selective action of the monitor beat 45 selectors of the several subchannels, the beat frequencies of subchannels operating with a common monitor beat oscillator should be in such relation that the beat frequency of one subchannel is not a harmonic of the beat frequency of the other 50 subchannel. This is secured by proper choice of the frequency of the monitor beat oscillator with respect to the frequencies of the several subchannels with which it is to cooperate, in the way described above. The remaining apparatus 55 of the monitoring system of the five subchannels may be substantially identical with the apparatus described in detail in connection with the subchannel C1, each channel being set for its particular beat frequency.

60 The receiving apparatus shown in Figs. 3 and 4 of the drawings comprises a reception input amplifier RIA, a reception beat detector RBD, a reception beat amplifier RBA, a reception channel selector RCS, a reception channel amplifier RCA, a reception channel rectifier RCR and a reception relay RE.

The reception input amplifier comprises a screen grid audion tube W1 having a cathode 201, an anode 202, a control grid 203, and a 70 screen grid 204. The input from an aerial AR is impressed upon the input electrodes of tube W1 across an input impedance 205, and an output impedance 206 is connected to the output electrodes of the tube W1, blocking condensers 207 and 208 completing the circuits.

The radio beat detector RBD comprises audion tubes W2, W3, having cathodes 210, anodes 211 and control grids 212, the tube W having also a screen grid 213. A tank circuit CL1 comprising an inductance 215 and a condenser 216 is connected across the input terminals of the tube W2. A tank circuit CL2 comprising an inductance 217, and a condenser 218 is connected in the output circuit of tube W2, by-pass condensers 219 and 220 completing the circuit connections. A non-selective impedance 221 is connected across the input electrodes of audion tube W3, and a primary winding of an audio frequency coupling transformer 222 is connected to the output electrodes of audion tube W3, by-pass condensers 224 and 225 and high frequency choke coils 226 completing the circuit connections. The two audion tubes W2 and W3 are connected in a reentrant ring circuit similar to the reentrant ring circuit of the transmitter oscillator TO by means of coupling connections 227, 228, including blocking condensers 229, 230. A cathode-heating source 231 and a plate and screen grid bias source 232 completes the circuit connections of the three tubes W1, W2 and 25 W3.

The tank circuits CL1 and CL2 are so adjusted that their frequency differs from the frequency of the received oscillations so that on combination therewith, a beat note of audio frequency 30 will be produced. For instance, assuming that the received frequency is 5,875.00 kilocycles, the tank circuits CL1 and CL2 are tuned for a frequency of 5,872.375 kilocycles so that when the two frequencies are combined a beat frequency 35 of 2625 cycles will result. The circuits of tube W3 are adjusted to deliver rectified beat currents to the output transformer 222, feeding the high frequency currents back to the input of tube W2.

I have found that such ring circuit in which the externally received oscillatory input is continuously recirculated together with the local oscillations produced in these circuits, operates as an extremely sensitive beat detector, and that due to the combination of the stable local oscillatory circuit for producing the beats, with effective amplification of the signals differing from the local oscillations, a strong and clear beat oscillation is produced in the output circuit of the tube W3. In other words, by using reentrant ring filter circuit amplification, there is obtained a stable beat oscillation; and the aperiodic character of the input and output circuit of the second audion tube W3 of the ring circuit permits 50 effective amplification of the audio beat frequency so that even very weak incoming signals will give a clear and ample beat note that is suitable for further amplification and reproduction of the signal.

The reception beat amplifier RBA comprises audion tubes W4, W5 having cathodes 235, anodes 236, and grids 237, with associated grid-biasing source 238 and plate source 239, the cathodes being supplied from the cathode supply source 231 referred to before. The output of the audio frequency coupling transformer 222 of the radio beat detector RBD is impressed upon the input electrodes of amplifier tube W4, and the output of this tube is impressed through the 70 audio frequency coupling transformer 240 upon the input electrodes of the second amplifier tube W5. The output of the latter tube is impressed upon a coupling transformer 241 which delivers through conductor 242, amplified beat frequency 75

currents to the radio reception channel selector RCS.

The reception channel selector RCS comprises screen grid tubes W6 and W7 having cathodes 5 251, anodes 252, control grids 253, and screen grids 254, with associated cathode heating source 255, plate current source 256, audio frequency choke coils 257 and by-pass condensers 258, 259. Tank circuits CL6, CL7 composed of inductances 10 and condensers are connected to the output electrodes by the audion tubes W6 and W7, and adjustable-tap input impedances 261, 262 are connected in the input circuits of the two tubes respectively. The amplified audio beat frequency 15 currents derived from the output transformer 241 are impressed through conductor 242 upon the input impedance 261 of audion tube W6 which serves to amplify the received beat frequency and to select through its tank circuit CL6 the frequency 20 to which tank circuit CL6 is tuned, suppressing other frequencies. The amplified output from tube W6 is impressed through conductor 264 including blocking condenser 265 upon the input impedance 262 of audion tube W7 which 25 further amplifies and through its tank circuits CL6, CL7 exercises a further selective action on the impressed beat frequencies. As a result, the 30 reception channel selector selects from the beat frequencies derived from the reception beat detector a beat frequency current having a frequency corresponding to the frequency of the particular subchannels. The selected beat frequency is at the same time amplified so that it is in sufficient strength for utilization in the further 35 apparatus.

The output of the reception channel selector is impressed through an input impedance 271 upon a reception channel amplifier RCA which comprises an audion tube W8 having a cathode 40 272, an anode 273 and control grid 274, with the associated cathode-heating source 275, plate current source 276, audio frequency choke coil 277 and by-pass condenser 278. The amplified output of the audion tube W8 is then passed through 45 a reception channel rectifier unit RCR comprising a double wave rectifier tube W9 and an amplifier tube W10. The rectifier tube W9 comprises double wave cathodes 281 and two anodes 282 cooperating therewith. An audio frequency 50 transformer 284 has a primary winding 285 connected to the output terminals of the amplifier tube W8, and a mid-tap secondary winding 286 connected to the anodes 282 of the rectifier tube W9. The rectified output is then derived through 55 conductors connected to the cathodes 281 and to the mid-tap of the secondary transformer winding 286, and impressed upon the input impedance 287 of the amplifier tube W10 having a cathode 288, anode 289 and control grid 290.

60 A cathode-heating source 291 supplies the cathodes of the tubes W9, W10 and a plate current source 292 supplies the plate circuit of the amplifier tube W10.

65 The rectifier beat oscillation currents passed by the rectifier tube W9 are amplified in the audion tube W10 and are impressed across the output impedance 295 upon the actuating coil 296 of a relay RE which may be a telegraph relay, or a relay 70 of an automatic telegraph such as used for wire telegraphy.

75 Monitoring apparatus may be connected to the output circuit of the audion tube W8 of the reception channel amplifier, as by means of a jack 297, or by means of a secondary winding of a

transformer 298 connected across the output terminals of audion tube W8.

In operation of the receiving system described above, the modulated impulses reaching the aerial AR of the receiver produce a circulation of current in the receiver antenna. These currents are amplified in the amplifier tube W1 which, as pointed out above, is not critically selective. The amplified oscillations are then impressed on the reception beat detector RBD where a local oscillation is combined with the received signals to produce a beat note which is then amplified in the several amplifying stages of the reception beat amplifier RBA. The amplified beat frequency currents are then impressed upon the several stages of the reception channel selector RCS where the beat frequency currents having the frequency of a particular subchannel are selected and amplified and then impressed upon the reception channel amplifier RCA for further amplification. The output of the latter amplifier is then rectified through the rectifier tube W9 and after further amplification in the tube W10 the signalling currents so derived are impressed upon the relay RE for actuating the telegraph recording or similar apparatus at the receiving station.

The arrangement described above is particularly useful when employed for the reception of signals of a number of subchannels. As shown in the drawings, the receiving system may be arranged for reception of signals transmitted, for instance, on five adjacent subchannels corresponding in this particular example to the five subchannels of the transmitting stations, i. e., for the subchannel frequencies of 5,873.50—5,874.250—5,875.00—5,875.75—5,876.50 kilocycles respectively. For such multiple channel receiving system I do not employ a complete set of receiving apparatus as described above for each subchannel, but I employ the reception input amplifier, reception beat detector and reception beat amplifier in common for the several subchannels. With such arrangement, the circuits and the elements of the reception input amplifier RIA, reception beat detector RBD and reception beat 40 amplifier RBA are so designed and correlated as to be substantially equally sensitive to high frequency signals of all the five subchannels that are to be picked up by the particular receiving apparatus.

Assuming, for instance, that the transmitting apparatus described in conjunction with Figs. 1 and 2 radiates a high frequency output which is a combination of signal-modulated energy of the five subchannels, C1, C2, C3, C4, C5 of the transmitting station, and that such modulated combined five subchannel output is received by the antenna AR of the receiving system, the input into the receiving aerial AR is then amplified in the reception input amplifier RIA and impressed on the radio beat detector RBD. The frequency of the local oscillation of the reception beat detector is so chosen as to give in combination with any of the five frequencies of the five subchannels of the transmitting station an audio beat frequency in the same way as the monitor beat oscillator. Thus, in the present instance, the local oscillations of the reception beat detector combined with the incoming signals of the five subchannels of the transmitting apparatus will give an output which is the resultant of five modulated beat frequencies of 1125 cycles, 1875 cycles, 2625 cycles, 3375 cycles and 4125 cycles. The resultant currents of these five beat frequencies are then further amplified in the 70 75

reception beat amplifier and then impressed through the common conductor 242 upon the reception channel selectors RCS of the five subchannels C1, C2, C3, C4, C5. A separate reception channel selector RCS, reception channel amplifier RCA, reception channel rectifier RCR and reception channel relay RE is provided for each of the five subchannels.

The tanks of the reception channel selectors 10 RCS of the five subchannels are tuned to the five different beat frequencies corresponding to the frequencies assigned to the five subchannels, that is, to the frequencies of 1125 cycles, 1875 cycles, 2625 cycles, 3375 cycles and 4125 cycles, so that 15 each reception channel selector picks out from the combined output of the reception beat amplifier RBA impressed upon the common conductor 242 only the currents of the beat frequency corresponding to the particular channel, and these selected beat-frequency currents are 20 then impressed upon the further apparatus of the particular channel for actuating the recording or other telegraph signalling apparatus.

I have found in practical tests that by utilizing 25 radio transmitting and radio receiving systems as described above, very good communication without interference may be obtained along closely spaced subchannels and that by the use of this arrangement, it is possible to obtain within the 30 available radio spectrum a much larger number of communication channels than by the other systems proposed heretofore.

A particular advantage of the system described above is the fact that a plurality of subchannels 35 operating on closely adjacent frequency bands are operated in combination as if they were parts of a single channel in such manner that there is excluded the possibility of interference with other communication channels. This is made 40 possible by the combination of the signalling energy of a plurality of subchannels in the transmitting station and the radiation of a combined wave representing the resultant of the signalling energy of the five subchannels at the transmitting 45 station; and the cooperation therewith of a receiving arrangement in which the received resultant radiations of the transmitting stations are amplified, stepped down by beat frequency oscillator amplifier and then the resultant beat 50 frequency resolved in its component beat frequencies corresponding to the beat frequencies of the several subchannels.

While a complete transmitting and receiving system is shown in this application including the 55 special oscillator constituting a part of the invention, only the transmitter is claimed herein as the other features disclosed will be separately claimed in other applications and are shown here merely by way of illustration as being closely related to the transmitter per se.

The invention resides not only in the general arrangement of apparatus and systems as described above but also in the specific arrangements of the apparatus of the various elements 65 of the system which are applicable to a variety of other uses than those described herein. Many modifications of the arrangements and details will suggest themselves to those skilled in the art, and it is accordingly desired that the appended claims be given a broad construction commensurate with the scope of the invention within the art.

I claim:

1. In a radio communication system, a plurality 75 of apparatus sets for producing oscillations

of a plurality of different but closely adjacent frequencies to operate a plurality of distinct communication channels, each set having a low energy master oscillator arranged to continuously produce oscillations of a frequency assigned to the particular communication channel, an amplifier for amplifying the output of said master oscillator, a second amplifier and means associated therewith for modulating the oscillatory output thereof under elimination of reactions on 10 said master oscillator through the interpositioning of said first amplifier between said master oscillator and said modulating means, a power amplifier connected to the output terminals of all of the amplifiers of the several sets for combining 15 the modulated output of the amplifiers of said sets and for further amplifying the combined output, an aerial for radiating the combined amplifier output of said power amplifier, said power amplifier being substantially equally effective in 20 amplifying the output of the apparatus of the several communication channels connected to it while discriminating against oscillations of frequencies remote from the frequencies of the individual channels connected to it, means for 25 heterodyning the unmodulated output from each of said master oscillators with a standard source of high frequency energy differing from the frequency of each of said master oscillators an amount such that relatively low frequency beats 30 will be produced between said standard source and each of said master oscillators, and means for comparing each of said low frequency beats with a standard generator having a frequency 35 equal to the normal frequency of the beat to which it is to be compared.

2. In a radio communication system, a power amplifier including audion tubes having input and output electrodes, a radiating aerial connected to said output electrodes, a plurality of channel oscillators arranged to oscillate at different frequencies for independently operating a plurality of distinct communication channels, an amplifier for each channel oscillator arranged to amplify the output thereof, a second amplifier arranged to further amplify the output from each of said channel oscillators, means associated with said second amplifier for modulating the amplified oscillations under elimination of reactions on 40 said channel oscillator by means of said first mentioned amplifier which is caused to act as a buffer between said channel oscillator and said second modulated amplifier, means for connecting the output electrodes of each of said channel 45 amplifiers to the input electrodes of said power amplifier for combining therein the individually modulated oscillatory energy derived from said plurality of channel oscillators, means for heterodyning the unmodulated output from each of said master oscillators with a standard source of high 50 frequency energy differing from the frequency of each of said master oscillators an amount such that relatively low frequency beats will be produced between said standard source and each of said master oscillators, and means for comparing each of said low frequency beats with a standard generator having a frequency equal to the normal 55 frequency of the beat to which it is to be compared.

3. In a radio communication system, the combination with transmitting apparatus for a plurality of communication channels comprising a master oscillator for each channel, means for amplifying and modulating the oscillations of 60

- the master oscillator of each channel, and means for radiating the modulated energy of each channel, of monitoring means for said communication channels comprising a standard oscillator arranged to oscillate at a frequency differing from the frequencies of all of said master oscillators, means for combining oscillatory currents derived from all of said master oscillators with the output of said standard oscillator to produce a combined beat current which is the resultant of beat currents of all of said master oscillators, means for selecting from the combined beat output beat frequencies corresponding to the combination of the oscillation of said standard oscillator with the oscillations derived from each master oscillator, and means for individually monitoring the several beats with standard oscillations of corresponding frequencies.
4. In a radio communication system, a plurality of apparatus for generating continuous high frequency oscillations of different frequency to operate a plurality of distinct communication channels, means for independently keying each separate channel, a low frequency standard oscillator for each channel and a common high frequency monitoring oscillator for the system, said common high frequency oscillator being adjusted to produce heterodyne beats of relatively low frequency with each of said plurality of high frequency generators, and means for continuously comparing said low frequency beats each with said low frequency standard oscillator, each of said low frequency oscillators being adjusted to produce a frequency of the same value as that of the beat normally produced between the common high frequency oscillator and the one of said plurality of high frequency generators to which said low frequency standard is being compared.

5. In a radio communication system, a plurality of channel oscillators for generating continuous high frequency oscillations for the purpose of effecting multi-channel communication, a single standard oscillator of slightly different frequency from the channel oscillators, means for heterodyning between the standard oscillator and the separate channel oscillators, thereby producing a plurality of beats substantially within the audio range of frequency, means for selecting, detecting and amplifying these beats and means for comparing these beats with a standard audio oscillator having a frequency, the same as that of the beat normally obtained between the channel oscillator and the high frequency standard oscillator.
6. In a multi-channel radio communication system, the combination with a transmitting apparatus for each channel comprising a master oscillator, an amplifier for amplifying energy derived from said oscillator, means for modulating the amplified energy, a power amplifier for amplifying simultaneously oscillations from all said channels, and an aerial for radiating the modulated amplified energy from said last amplifier, of a monitoring system comprising a standard oscillator arranged to generate an oscillation differing from the frequency of one of said master oscillators by an audible frequency, means for deriving an unmodulated oscillatory current from any of said master oscillators and combining it with the output of said standard oscillator to produce an audible beat note, a second standard oscillator arranged to produce an oscillation of the frequency of said beat note, and means for monitoring the oscillation of said second standard oscillator against the derived beat oscillation of one of the master oscillators.

EARL L. KOCH.
